GARMENT HANGER

Paul Legus, Minneapolis, Minn.

Application November 6, 1933, Serial No. 696,806

1 Claim. (Cl. 223—88)

My invention provides an improved garment hanger especially adapted for the hanging of coats, vests and trousers and, generally stated, consists of the novel construction, combinations and arrangement of parts hereinafter described, and defined in the claim.

The objects of the invention are simplicity of construction, low cost and ability to properly hold a complete suit of men's clothes. Several forms of the device are illustrated in the accompanying drawing, wherein like characters indicate like parts throughout the several views.

Referring to the drawing:

Fig. 1 is a perspective showing what is believed to be the preferred form of the garment hanger; and

Fig. 2 is a perspective showing a slightly modified form of the garment hanger.

Referring first to the construction illustrated in Fig. 1, it will be noted that the body of the hanger is made from a single piece of wire, bent to form a hook-like anchoring device 8, a bowed upper portion 9, and a transverse lower portion 10, which latter is formed with corrugations 11. The corrugations 11 are preferably of a sort of saw-toothed arrangement, those on the opposite sides having reverse bevels. Mounted on the corrugated portions 11 are trouser-engaging hanger hook arms 12 and 13. For an important purpose, the arm 12 is made much longer than the arm 13. Each arm is provided with an eye 12^a or 13^a that slidably engages with the corrugated portions 11. At their lower ends, each arm is formed with wide approximately horizontal ends 12^b or 13^b, in the form of hooks. Here it is important to note that these depending arms 12 and 13 hang in vertical planes approximately at right angles to the horizontal ends or hooks 12^b and 13^b.

In the use of this hanger, the hook arms 12 and 13 can be adjusted to the desired spacing. It is a known fact that men's trousers are commonly and generally provided with belt loops located, two close to the rear and two close to the front and that the trousers are cut lower in front than at the rear. The long hooks are arranged to engage the loops at the front of the trousers and the short hooks are arranged to engage the loops at the rear of the trousers, so that a pair of trousers hung on these hooks will be hung in flat

vertically suspended condition, which tends to keep them in good shape so as to maintain the press in the trousers. Moreover, the transversely extended horizontal lower portions of said hooks are made wide enough or are sufficiently extended in a horizontal direction so that at least two pairs of trousers can be hung on the same hooks at the same time. Hanging of trousers as above stated obviously can be properly accomplished only by their hooks having their lower ends extended in planes transversely of or at right angles to the body of the hanger.

Of course, it will be understood that vests and coats can be hung on the bowed upper portions 9 of the coat hanger just described.

The hanger illustrated in Fig. 2 is made up of a single wire bent to form a hook-like anchoring device 14, an upper portion 15 and a transverse lower portion 16, which latter is formed with upwardly bent corrugations or projections 17 that afford hook-restraining teeth.

In this arrangement, the long hooks 18 have eyes 18^a that are adjustably hung on the lower rod 16 and are provided at their lower ends with the transversely extended trouser engaging portions 18^b. The short hooks 19 in this arrangement, are provided with eyes 19^a and lower end portions 19^b applied as shown.

From the foregoing, it is evident that the improved coat hanger is capable of various modifications within the scope of the appended claim. The corrugations formed as illustrated in connection with Fig. 1 are preferred because they best restrict sliding movements of the hooks 12 and 13 toward each other, but nevertheless, permit intentional adjustments, easily performed manually but not accidentally.

What I claim is:

A coat hanger comprising a body member formed from a single piece of wire bent to form a bowed upper portion and a transverse lower rod, the latter being corrugated, and arms adjustably hung on said corrugated rod, said arms having lower trouser-engaging end portions extending in planes transversely and approximately at right angles to the plane of said adjustable arms, said arms hanging approximately at right angles to the horizontal plane of the body portion of said hanger.
